DESIGN FOR A SHOE

Roy Maling, Chestnut Hill, Mass.

Application March 6, 1948, Serial No. 144,948

Term of patent 14 years

(Cl. D7—7)

To all whom it may concern:

Be it known that I, Roy Maling, a citizen of the United States, residing in Chestnut Hill, in the county of Middlesex and State of Massachusetts, have invented a new, original, and ornamental Design for a Shoe, of which the following is a specification, reference being had to the accompanying drawing, forming part thereof.

I claim:

The ornamental design for a shoe, as shown.

ROY MALING.
